CLAIM

The ornamental design for a two part interlocking plastic pallet, as shown and described.

DESCRIPTION

FIG. 1 is a perspective top view of a two part interlocking plastic pallet comprised of a base, a deck and a plurality of connectors showing our new design;

FIG. 2 is a top plan view of the deck thereof;

FIG. 3 is a right elevation view thereof with the left, front and rear elevation views being the same; and,

FIG. 4 is a bottom plan view of the base thereof.
